CLAIM

The ornamental design for a golf bag, as shown and described.

DESCRIPTION

FIG. 1 is a top left side perspective view of a golf bag showing a new design;

FIG. 2 is a top right side perspective view of a golf bag showing a new design;

FIG. 3 is a front side plan view of the golf bag as shown in FIG. 1;

FIG. 4 is a rear side plan view of the golf bag as shown in FIG. 1;

FIG. 5 is a left side plan view of the golf bag as shown in FIG. 1;

FIG. 6 is a right side plan view of the golf bag as shown in FIG. 1;

FIG. 7 is a top plan view of the golf bag as shown in FIG. 1;

FIG. 8 is a bottom plan view of the golf bag as shown in FIG. 1;

FIG. 9 is a top left perspective view of the golf bag showing a new design shown in FIG. 1 with a shoulder strap attached; and,

FIG. 10 is a top right perspective view of the golf bag showing a new design shown in FIG. 1 with a shoulder strap attached.

In the drawings, the broken lines are for the purpose of illustrating certain stitching that does not form part of the claimed design. In FIGS. 1-10, the dash-dot-dash broken lines depict portions of a golf bag that form no part of the
